METALLIC BEDSTEAD

Clarence L. Dewey, Elkhart, Ind.

Application November 22, 1943, Serial No. 511,239

9 Claims. (Cl. 5—280)

The bedstead of the present invention is intended to conform in its style and general appearance to wooden bedsteads of attractive style and finish while at the same time being so constructed that its constituent parts can all be easily formed from metallic sheets and tubing fabricated by methods of quantity production and so assembled that the resulting structure, while light in weight and graceful in design, will nevertheless possess abundant elements of strength, 10 rigidity, and durability due to the formation of the individual parts and the means employed in their assembly. Further details of the present invention will be set forth in the specification in conjunction with the accompanying drawings. 15 wherein—

Fig. 1 is an elevation of the head of the bed as viewed from the inside;

Fig. 2 is an elevation of the foot as viewed from the outside;

Fig. 3 is a sectional elevation of the head taken on line 3—3 of Fig. 1;

Fig. 4 is a similar view taken on line 4—4 of Fig. 2;

Fig. 5 is an enlarged detail in section taken on line 5—5 of Fig. 1 showing one of the hook and socket connections for supporting the sills from the corner posts or standards;

Fig. 6 is a section taken on line 6—6 of Fig. 5;

Figs. 7 and 8 are cross sections of one of the posts taken on lines 7—7 and 8—8 of Fig. 1;

Fig. 9 is a detail of the cap plate for the head;

Fig. 10 is a detail showing how the finish strip for the upper edge of the head is fitted into place; and

Fig. 11 is a sectional detail taken on line 11—11 of Fig. 9.

The bedstead as a whole comprises a headboard 20, a footboard 21, connecting side sills 22, head posts 23 and foot posts 24. In its general appearance it resembles a conventional four poster bed.

The headboard is formed of front and back upper walls 25 and 26 of stiff sheet metal and a single lower base wall 27 of heavier and stiffer gauge metal. The assembly of these walls into a unified structure provides a headboard of generally rectangular shape and with rounded upper corners and conformable in style to wooden furniture of tasteful design.

The front wall of the headboard is die-pressed to provide inwardly depressed upper and lower panels 28 and 29, and the back wall is likewise die-pressed to provide inwardly depressed upper and lower panels 30 and 31, the faces of which

5 contact with, and are spot welded to, the faces of the panels 28 and 29 so that the resulting structure is one of greater depth in the areas surrounding the panels where the metal wall surfaces are somewhat widely separated and of lesser depth where the panel surfaces contact with one another.

This offsetting of the metal to impart an outstanding margin around and between the depressed panels, not only greatly stiffens the headboard but imparts to the surface an attractive paneled effect while the depressed panel surfaces afford extended contact areas for the uniting of the front and rear walls together.

Furthermore, the greater depth of the margins imparts a substantial appearance to the headboard as a whole and renders inconspicuous its relative thinness in the paneled areas where the walls contact with one another, thus simulating 20 the appearance of a paneled wooden bedstead of excellent design and craftsmanship.

The lower margin of the front wall 25 is stuck back to provide a flange 32, the edge of which abuts against the front surface of the base wall 27 which is offset forwardly from end to end to afford a ledge 33 against which the outer face of the flange abuts. The base wall is offset rearwardly at an intermediate level to provide a shoulder 34 and offset forwardly at a lower level to provide a shoulder 35 while the base wall along its lower margin is provided with a rearwardly projecting flange 36. This alternate offsetting of the metal wall from opposite sides affords on the front a center depressed panel 37 and on the rear, upper and lower panels 38 and 39 which greatly stiffen the base wall and enable a single thickness of heavier metal to sustain the upper portion of the headboard and afford the necessary rigidity to withstand the strains to which this portion of the bedstead is subjected.

Above the ledge 33 the base wall is extended in the form of a flat plate which bridges the space behind the lower portion of the back wall 26 and overlaps the rear surfaces of the lower panels 29 45 to which the base wall is spot-welded at the point 40. Spot-welding is also applied to the contacting surfaces of the inner and outer walls at the points 41 and likewise may be applied to the area of contact between the flange 32 and the ledge 33. The back wall 26 terminates at a level adjacent the upper edge of the base wall, and the end margins of the front and back walls are obliquely flanged at 42 and 43 (Fig. 8) to make contact and union with the posts 23 in a manner 50 presently to be described.

The footboard is a counterpart in structure to the headboard except for the omission of a base wall so that the description and the reference numerals previously given, apply equally to the footboard and need not be repeated. However, instead of a base wall, the footboard is stiffened along its lower margin by a reenforcing plate 44 which is offset to provide a center channel 45, the face of which abuts against the lower portion of the front wall to which it is united by spot welding 46 while the lower edge of the plate is stiffened by a forwardly struck flange 47 which nests against the flange 32. The upper portion of the reenforcing plate overlaps the inwardly depressed surfaces of the lower panels 29 to which it is united by spot welds 48. The ends of the reenforcing plate are obliquely flanged as at 49 (Fig. 7) which likewise illustrates the oblique flanging of the ends of the base wall of the headboard.

The upper rounded edges of the headboard and footboard are overlapped by the finishing strips 50 shown in detail in Figs. 9, 10, and 11. These strips are of inwardly opening channelled formation and are constructed of relatively flexible metal or other suitable material which are given an ogee curved configuration along the edges 51, which on each side provides a groove 52 for the reception of inturned flanges 53 formed along the upper edges of the front and back walls of the headboard and footboard and around the arched corners. The formation of the channels 52 correspondingly narrows the width of the strip at an intermediate point, giving it the shoulder and neck formation shown in Fig. 11, and to permit this neck portion to occupy a position intermediate the inturned flanges 53, the latter are of less depth than the offsets along the panels 28 and 30.

Figs. 9 and 10 indicate how the finishing strips are slipped into position. In order to provide clearance for the entering of the end of the strip into engaging relation with the upper edge of the headboard or footboard, the edge is provided in its center with a notch 54, which provides a gap in the flanges 53 and thus permits the end of the finishing strip to slip onto the exposed butt ends of the flanges which register with the side grooves 52 in the finishing strip. When such engagement of the parts has been effected, the strip will be flexed sufficiently to clear the opposite edge of the notch 54, and then thrust along the edge of the headboard or footboard until its end is flexed around the curved corner and reaches a position which will contact with the adjacent post, thus closing the gap and providing a suitable finish for the edge. After companion finishing strips have been oppositely inserted through the notch 54, the latter is closed by the insertion of a cap 55 of inverted channel formation which is slipped into place to overlap the edges of the notch.

Save for length, the corner posts are of identical construction, so that a description of one will apply to all. Each post is formed from a section of tubing which is indented to give it the four pointed star shape in cross section as shown in Figs. 7 and 8, with rounded ridges 56 and intervening grooves 57, the walls of which are flat and diverge from one another at a wide angle.

Each post is tapered from its medial region in each direction and terminates in a closed dome-shaped tip 58 and a closed flattened foot 59 for floor contact. The bases of the grooves are throughout equidistant from the longitudinal

axis of the post, and the post being tapered, this results in a progressive reduction in the depth of the grooves which terminate short of the foot and tip of the post, which remain circular in cross section. These end portions, however, are above and below the area of contact of the end edges of the headboard and footboard so that contact throughout will be made with grooved portions of the posts.

These parts are united in the manner shown in Figs. 7 and 8. It will be noted from Fig. 8 that the obliquely disposed flanges 42 and 43 on the ends of the front and rear walls make face contact with the diverging walls of the grooved portion of a post and that the front panel only is united thereto preferably by a line of brazing 60. This is because in the assembling of the parts and the concealment of the brazing, it is necessary first to unite the front walls to the posts by interior brazing and thereafter secure the rear walls to the front walls, and this technique precludes the possibility of applying concealed brazing to both of the walls although close contact between the oblique flanges 43 is maintained when the two walls are united and spot-welded together in the manner previously described.

The end flanges 49 of the base wall 27 are secured by a line of brazing 61 as shown in Fig. 7. This method of uniting the head and footboards to the corner posts conceals the brazing and affords a smooth and sightly joint so that the exterior finish of the bedstead is not marred by the exposure of the means employed in uniting the parts together. Each side sill 22 is composed of rigid flat plate material which along its upper margin is recurved inwardly to afford an inverted channel formation presenting a broadened upper edge 62 and at its lower edge, the sill is inturned to afford a broad inwardly extended ledge 63 for the support of box springs or the like.

At each end of the sill is a stiff end plate 64 which sockets into the channel under the edge 62 and rests upon the ledge 63. The end plate is united by lines of brazing or arc welding 65 so that a firm and rigid union is provided and the sill is strongly reenforced at each end. Each end plate has projecting from its outer edge a pair of hooked fingers 66, which are entered through slots 67 in a socket plate 68 which is brazed or arc welded along lines 69 across the inwardly facing groove in the adjacent corner post, thus affording a rigid socket for the reception of the hooked fingers which support the sill, and permitting the bedstead to be disassembled in the conventional manner. In order to afford sufficient clearance for the insertion of the hooked fingers, the base of the adjacent groove is provided with vertically extending apertures 70, which are flanged along their margins 71 by the intrusion of the metal displaced from the slots as shown in Fig. 7.

The structure of the bed as a whole is one which throughout conceals from view any raw or unfinished edges or joints which would tend to mar its appearance or interfere with the application of a suitable and attractive finish which may be of enamel of tasteful colors or in imitation of costly woods, while the paneling of the head and footboards and the tapering and grooving or fluting of the posts not only conserves weight and increases the rigidity of the structure but likewise provides for the concealed union of the head and footboards, while at the same time conforming the appearance of the bedstead

to accepted principles of harmonious designing.

I claim:

1. In a metallic bedstead, the combination of head and footboards, each constructed of front and back metallic walls indented in selected areas to form depressed panels, the inner surfaces of the indented areas being in contact, front and rear corner posts of tubular construction and grooved to receive the end edges of the head and footboards, said end edges being provided with inturned flanges in face contact with the walls of the respective grooves, means for uniting the end edges within said grooves, and side sills provided at each end with means adapted to engage with the intermediate portion of the contiguous post for uniting the parts in assembled relation.

2. In a metallic bedstead, the combination of head and footboards, each constructed of front and back metallic walls indented in selected areas to form depressed panels, the inner surfaces of the indented areas being in contact and secured to one another by a thermally applied union, front and rear corner posts of tubular construction and grooved to receive the end edges of the head and footboards, said end edges being provided with inturned flanges in face contact with the walls of the respective grooves, means for uniting the end edges within said grooves, and side sills provided at each end with means adapted to engage with the intermediate portion of the contiguous post for uniting the parts in assembled relation.

3. In a metallic bedstead, the combination of head and footboards, each constructed of front and back metallic walls indented in selected areas to form depressed panels, the inner surfaces of the indented areas being in contact and secured to one another by a thermally applied union, finish strips overlapping the upper edges of the front and back walls of the head and footboards and interlocking therewith to conceal said edges, front and rear corner posts of tubular construction and grooved to receive the end edges of the head and footboards, said end edges being provided with inturned flanges in face contact with the walls of the respective grooves, means for uniting the end edges within said grooves, and side sills provided at each end with means adapted to engage with the intermediate portion of the contiguous post for uniting the parts in assembled relation.

4. In a metallic bedstead, the combination of head and footboards, each constructed of front and back metallic walls indented in selected interior areas to provide depressed panels having their inner wall faces in contact with one another, with the surrounding wall areas standing in spaced relation, means for uniting the contacting areas, corner posts each having a longitudinal groove confronting an end edge of either the head or footboard, each of said end edges having an inturned flange in facewise contact and union with one of the walls of the associated groove, and side sills, each having at each end engaging means coacting with the adjacent post.

5. In a metallic bedstead, the combination of head and footboards, each constructed of front and back metallic walls indented in selected interior areas to provide depressed panels having their inner wall faces in contact with one another, with the surrounding wall areas standing in spaced relation, means for uniting the contacting areas, the headboard being extended downwardly by the provision of a base wall overlapping

the lower portion of one of the panelled walls and secured thereto, and the footboard being stiffened along its lower portion by the provision of a channeled reenforcing plate secured to one of the walls thereof, corner posts each having a longitudinal groove confronting an end edge of either the head or footboard, each of said end edges having an inturned flange in facewise contact and union with one of the walls of the associated groove, and side sills, each having at each end engaging means coacting with the adjacent post.

6. In a metallic bedstead, the combination of head and footboards, each constructed of front and back metallic walls indented in selected interior areas to provide depressed panels having their inner wall faces in contact with one another, with the surrounding wall areas standing in spaced relation, means for uniting the contacting areas, finish strips having lateral channels engaging the upper margins of the front and back walls of the head and footboards respectively and overlapping the crank between said walls, corner posts each having a longitudinal groove confronting an end edge of either the head or footboard, each of said end edges having an inturned flange in facewise contact and union with one of the walls of the associated groove, and side sills, each having at each end engaging means coacting with the adjacent post.

7. In a metallic bedstead, the combination of head and footboards, each constructed of front and back metallic walls indented in selected interior areas to provide depressed panels having their inner wall faces in contact with one another, with the surrounding wall areas standing in spaced relation, means for uniting the contacting areas, the headboard being extended downwardly by the provision of a base wall overlapping the lower portion of one of the panelled walls and secured thereto, and the footboard being stiffened along its lower portion by the provision of a channeled reenforcing plate secured to one of the walls thereof, finish strips having lateral channels engaging the upper margins of the front and back walls of the head and footboards respectively and overlapping the crack between said walls, corner posts each having a longitudinal groove confronting an end edge of either the head or footboard, each of said end edges having an inturned flange in facewise contact and union with one of the walls of the associated groove, and side sills, each having at each end engaging means coacting with the adjacent post.

8. In a metallic bedstead, the combination of head and footboards, each constructed of front and back metallic walls indented in selected interior areas to provide depressed panels having their inner wall faces in contact with one another, with the surrounding wall areas standing in spaced relation, means for uniting the contacting areas, the headboard being extended downwardly by the provision of a base wall overlapping the lower portion of one of the panelled walls and secured thereto, and the footboard being stiffened along its lower portion by the provision of a channeled reenforcing plate secured to one of the walls thereof, corner posts each having a longitudinal groove confronting an end edge of either the head or footboard, each of said end edges having an inturned flange in facewise contact and union with one of the walls of the associated groove, and side sills, each having at each end an end plate provided with downturned hooked fingers, and a socket plate

secured to each post and provided with slots adapted to receive said fingers.

9. In a metallic bedstead, the combination of head and footboards, each constructed of front and back metallic walls indented in selected interior areas to provide depressed panels having their inner wall faces in contact with one another, with the surrounding wall areas standing in spaced relation, means for uniting the contacting areas, the headboard being extended downwardly by the provision of a base wall overlapping the lower portion of one of the panelled walls and secured thereto, and the footboard being stiffened along its lower portion by the provision

of a channelled reenforcing plate secured to one of the walls thereof, finish strips having lateral channels engaging the upper margins of the front and back walls of the head and footboards respectively and overlapping the crack between said walls, corner posts each having a longitudinal groove confronting an end edge of either the head or footboard, each of said end edges having at each end an end plate provided with downturned hooked fingers, and a socket plate secured to each post and provided with slots adapted to receive said fingers.

CLARENCE L. DEWEY.
